UNITED STATES PATENT OFFICE

CHARLES C. BLACKMORE, OF DAYTON, OHIO

TOY CANNON

Application filed January 16, 1929. Serial No. 332,992.

My invention relates to cannons.

It is the object of my invention to provide a construction particularly adapted for toy cannons, toy pistols, and other toy firearms, in which a fulminate cap is employed to light a fuse of a fire cracker and the explosion of the fire cracker results after ejecting the body of the fire cracker from the barrel of the gun.

10 It is the particular object of my invention to provide a novel form of breech mechanism and firing mechanism for firing the cap, positioning the fuse of the fire cracker and lighting the fuse from the cap when it is so 15 positioned.

It is an essential object of my invention to provide a simple structure so arranged that it must be ventilated positively between each firing in order to prevent explosions, 20 during loading or otherwise, prematurely due to residual gases in the gun, burning portions of the charge, etc.

It is my object to provide such a structure having these essential factors for safety and 25 operation, while at the same time maintain them with such simplicity that a child can operate them safely, and they can be economically manufactured and sold for a small sum.

30 My invention, meeting these conditions, is illustrated in the attached drawings, as follows:

Figure 1 is a plan view of the one embodying my invention.

35 Figure 2 is a side elevation thereof.

Figure 3 is a section of the line 3—3 of Figure 1.

Figure 4 is a section of the line 4—4 of Figure 3.

40 Figure 5 is a section of the line 5—5 of Figure 2.

Figure 6 is an inside elevation of the detachable breech block and firing mechanism.

Referring to the drawings in detail, 1 45 designates the trail of the gun which is mounted on the axle 2 to be carried by the wheels 3.

The barrel 4 of the gun is mounted on the trunnions 5 in the trail 1. The end of the 50 trail is provided with the usual spade 6 pro-

vided with an eye 7 through which passes the lanyard 8.

Mounted on the underside of the barrel of the gun, adjacent the breech, is a hammer block 9 to which is pivoted at 10 a hammer 11 having a hammer head 12 for striking the firing pin 13, and a thumb piece 14 to facilitate its being cocked. A lanyard arm 15 provided with an eye 16 is connected to the lanyard 8 so that when the lanyard is 60 pulled the hammer can be moved to firing position.

Within the block 9 is a spring 17 which serves to maintain the hammer in either firing or ready to fire positions and serves to 65 impel the hammer against the firing pin 13.

The breech of the gun is provided on either side thereof with a pair of lateral extending breech lock lugs 18 which are adapted to be engaged by overlapping breech block fingers 70 19 carried on the breech block plate 20 which crosses the breech end of the gun. These lugs 18 are sufficiently cam shaped on the faces 21 to form a locking engagement with the overlapping fingers 19. The firing pin 13 has a head 22 which reciprocates within an open topped firing chamber 23 adapted to receive the fulminate cap 24. This chamber positions the fulminate 25 opposite the firing opening 26 into which is projected the fuse 27 of the fire cracker 28 which has its usual powder charge 29.

Operation.—The gun is loaded by inserting the fire cracker into the barrel with the fuse in position as indicated. This insertion is through the breech end of the gun. The breech block has its firing chamber loaded with the fulminate cap. The block is applied to the gun and rotated into locking position with the fuse 27 in the aperture 26.

During this operation the hammer and firing head are held in inoperative position by the spring 17.

Upon pulling the lanyard 8 the hammer is snapped, the firing head drives the firing pin 13 against the fulminate 25, exploding it. This in turn ignites the fuse 27 which in turn ignites the powder 29. The resulting cap explosion ejects the fire cracker 28 out of the gun where the cracker explodes.

In a toy gun with a barrel about 6 to 8 inches long, the fire cracker is ejected about 30 feet at an ordinary elevation of the gun as indicated in Figure 2.

I desire to comprehend within my invention such modifications as may be clearly embraced within my claims and the scope of my invention. It will be understood any means may be employed for ejecting by explosion and simultaneously igniting the charge; it will be further understood that the ejected charge will explode depending on the length of the fuse and the size of the ejecting charge.

Having thus fully described my invention what I claim as new and desire to secure by Letters Patent, is:

1. In a cannon, a barrel, a cap carrying fulminate chamber independent of the barrel and means for positioning the fuse of a fire cracker in said chamber.

2. In combination in a cannon, a barrel, a breech block therefor, a firing chamber in said block, a firing pin and firing head in said chamber, said chamber having a firing port and a loading port, a firing hammer adapted to engage said pin mounted on said gun, and means for positioning a shell in said gun.

3. In combination, in a cannon, a barrel, a breech block therefor, a firing chamber in said block, a firing pin and firing head in said chamber, said chamber having a firing port and a loading port, a firing hammer adapted to engage said pin mounted on said gun, and means for positioning a shell in said gun, said means being so arranged that a fuse in said shell will project in said firing port.

4. In combination, in a gun, a gun barrel, a rotatable breech block, a firing chamber in said block having the upper end thereof open for loading, a firing pin and firing head reciprocating in said chamber.

5. In combination, in a gun, a gun barrel, a rotatable breech block, a firing chamber in said block having the upper end thereof open for loading, a firing pin and firing head reciprocating in said chamber, said chamber having a firing port opposite said head and means in said gun barrel for positioning an explosion charge, shell and fuse so that said fuse is located in the firing port of the firing chamber.

6. In combination, in a gun, a gun barrel having a shell tube and a breech chamber, a rotatable breech block adapted to be located on the breech end of the barrel and partially in said breech chamber, a firing chamber in said breech block having a firing opening registering with the gun barrel to receive a shell fuse and a firing pin reciprocating in said block with its head in said firing chamber.

7. In combination, in a gun, a gun barrel having a shell tube and a breech chamber, a rotatable breech block adapted to be located

on the breech end of the barrel, a firing chamber in said breech block having a firing opening registering with the gun barrel to receive a shell fuse and a firing pin reciprocating in said block with its head in said chamber.

8. In combination, in a gun, a gun barrel having a shell tube and a breech chamber, a rotatable breech block adapted to be located on the breech end of the barrel, and partly in said breech chamber a firing chamber in said breech block having a firing opening registering with the gun barrel to receive a shell fuse and a firing pin reciprocating in said block with its head in said firing chamber, a spring pressed firing trigger yieldingly held in firing or cocked position.

9. In combination, in a gun, a gun barrel having a shell tube and a firing chamber, a rotatable breech block adapted to be located on the breech end of the barrel, a firing chamber in said breech block having a firing opening registering with the gun barrel to receive a shell fuse and a firing pin reciprocating in said block with its head in said chamber, a spring pressed firing hammer yieldingly held in firing or cocked position, and a lanyard for moving said trigger from cocked to firing position.

10. In combination, in a gun, of a barrel, a freely detachable breech block, means on said breech block for supporting and igniting a firing charge, and means in said barrel for locking a fused shell in line with the firing charge for the ignition of said fuse, said parts being so arranged that the complete removal of the breech block is necessary for reloading of the firing charge whereby the gun is completely ventilated before each firing operation.

11. In combination, a gun barrel cam lugs on the breech end thereof, a breech block plate having forwardly and laterally projecting cam fingers engaged with said lugs to lock the breech plate to the gun.

12. In combination, a gun barrel, cam lugs on the breech end thereof, a breech block plate having forwardly and laterally projecting cam fingers engaged with said lugs to lock the breech plate to the gun, a firing chamber and firing pin carried by said plate.

In testimony whereof I affix my signature.

CHARLES C. BLACKMORE.
